CONCRETE WALL FORM

Fred F. Stadelhofer, Berkeley, Calif.

Application: June 27, 1945, Serial No. 601,851

12 Claims. (Cl. 25—131)

1

This invention, a concrete form and method of forming concrete walls provides an improvement over existent methods of forming the walls of concrete structures because of the economy in construction involving the saving of materials, time and labor, rigidity and uniformity of the structure, the aesthetic appearance created and particular adaptability to the most modern types of structures. It eliminates the cost of insetting of frames and preformed ornamenting and lighting or glazing, and greatly increases the speed of construction.

The method is particularly adapted to the construction of manufacturing plants and workshops, art studios, and to such portions of private dwellings where an abundance of daylight is desirable. It is also very desirable for exposed walls of retail and wholesale establishments and the like because of the uniformity of lighting. It can also be used in the construction of roofs where skylighting is desirable.

The objects and advantages of the invention are as follows:

First, to provide a method by which concrete walls of structures can be most economically and quickly completed, with a minimum of time, labor and material.

Second, to provide a method as outlined by which all insertable elements are cast directly into the wall with the pouring of the concrete and including all light-transmitting elements, door and window frames and the like so that after-fitting, grouting, and glazing, will be dispensed with.

Third, to provide a method as outlined by which light transmitting elements, door and window frames, and ornamental devices can be cast in place flush with either side of the wall irrespective of the thickness of the wall.

Fourth, to provide a means for casting the walls of concrete structures in which insertable elements such as light transmitting elements, door and window frames, and ornamental elements, initially form a part of the form, and after pouring of the concrete, form an integral part of the wall.

Fifth, to provide a form as outlined in which inserts such as glass-blocks can be arranged in any desired pattern or arrangement, with the inserts functioning as spacers between the walls of the form until the concrete is poured and set, and thereafter forming an integral part of the wall structure.

In describing the invention reference will be made to the accompanying drawings, in which:

Fig. 1 is a side elevation shown with portions

2

of one side wall broken away to illustrate the interior construction of the form.

Fig. 2 is an end elevation of Fig. 1.

Fig. 3 is an enlarged fragmentary sideview of one of the glass block retainers.

Fig. 4 is a section taken on line 4—4 of Fig. 3.

Fig. 5 is a fragmentary enlarged sectional view of one method of connecting a series of forms and extensions.

Fig. 6 is an enlarged section through a wall and one of the glass blocks as formed by my method.

Fig. 7 illustrates the adaptability of the arrangement for replacement of broken glass blocks by conventional window or plate glass.

The invention consists of a method of casting concrete walls in which all inserts for the wall are cast in place instead of being fitted after the wall has been poured and set. By this method, all pre-cast or pre-formed elements which are to be mounted in the wall are positively located in their correct positions and immovably secured in the form.

The method involves a form or plurality of forms each of which consists of two side plates or panels, the various elements which are to be included in the finished wall and which are to initially function as spacers in the form, and tie elements to prevent spreading of the panels under fluid pressure during pouring of the concrete, and to secure the inserts in the exact positions which they are to occupy in the specific portion of the wall to be formed by that form.

Referring to Figs. 1 and 2, it will be noted that the panel 10 is provided with insert locators and retainers 11, while the panel 12 has no such locators or retainers. With this arrangement the glass block 13 will be flush with the side 14 (Fig. 6) the finished wall 15 formed by the panel 12, and inset from the other side 16 formed by the panel 10. In case the wall is not required to be any thicker than the glass block, the respective panels will contact the respective ends of the block with one of the panels provided with relatively thin locators and retainers 17, the panels 10 being illustrated with deep-set locators and retainers 11 on one side and shallow locators and retainers 17 on the other side, whereby the panel need merely be turned inside out for narrow walls. These locators and retainers are made readily removable as indicated at 18 and are required on only one panel if the other end of the block is to be flush with the face of the wall, but if the block 13 is to be centered, then the locators and retainers are provided on both panels. The block is located and retained in position by the wall 19 and

rests on the surface 20, therefore the thickness of the finished wall will be equal to the thickness of the block or insert 13, plus the height of the surface 20 above the panel face 21 if one side of the block is to be flush, and plus the combined height of the surfaces 20 above the respective panel faces if the block is not to be flush with either wall. The height can be varied to suit the blocks or other inserts to be used and the specific thickness of wall desired.

Through-fastening devices 22 which may consist of bolts or other types of fastening elements which are well known in the art, are spaced to give ample support against fluid pressure and to immovably retain the blocks or inserts in position during pouring of the concrete. These fastening devices are located in the paths of the reinforcing rods 23 used in the wall structure and provide support for these rods. Special hand holes to permit tying the lower ends of the reinforcing rods to the fastening devices are provided with cleated covers 24 secured by one of the fastening devices as shown. With this arrangement, the blocks can be arranged symmetrically throughout the wall and can be left out at any point, it merely being necessary to remove the locator and retainer, and for locating a door or window frame 25 or the like, all locators and retainers are removed from the area to be occupied by the frame as indicated at 26 and suitable locators, spacers and retainers provided to suit the particular frame for location in the desired position in the wall.

To form a header, either the top row of blocks may be omitted along with their locators and retainers, or an extension 28 may be provided.

Where a number of forms may be set up for simultaneous pouring of concrete, connections are provided for the adjoining ends, and which may consist of cleats and clips not shown, but which are not so desirable because it would not permit direct reversal of the panels as is possible with either the latches 29 or the plates 30, both of which are recessed in slots in the ends of the panels but the latter of which is preferable because it forms a seal at the joint. As will be noted, a slot 31 is formed endwise throughout the height of the panel, the plate is inserted and secured by means of screws 32 as is clearly illustrated in Fig. 5, the screws being just long enough to extend through the panel and being secured in threaded apertures in the plate, and the plates are therefore readily removable when not needed.

If the block pattern is to be continuous, closures in the form of plugs 33 cut to fit between the outer sides of two adjacent blocks and just between the adjacent corners, and secured in position by bolts 34 are provided. When the section has been poured and is set, the outer halves of the last tier of blocks will extend beyond the concrete, then if the form is reloaded and placed in proper position the concrete will fill around the remainder of the previous blocks and provide an unbroken pattern.

It will be noted that the base sections can be poured along with the foundation, by supporting the wall section form on top of the foundation form 35.

Obviously, there is always a possibility that after the building is completed and in use, certain of the blocks may be broken, and this system provides the most advantageous arrangement for repairing any such breaks, because the broken block can be completely broken out with very little effort, and a new block without the cir-

cumferential locking ribs can be inserted, or any other type of filler can be substituted, the best substitution in such case being a pane of glass 36 which will seat against the shoulder 37 formed by the ridge 38 or 17 left by the locator and retainer, with the glass puttied in place as indicated at 39.

Thus all elements which are to form a part of the wall structure of the building initially function as spacers and forms in the concrete-pouring form, and after the concrete is set and the forms removed, these elements no longer are a part of the form, but an integral part of the building, cast right in place.

As previously mentioned, any type of ornamental or other type of block can be cast in the wall, but the main purpose is to cast conventional glass blocks in a concrete wall to provide the best lighting effect, and an exceptionally strong wall with complete sealing around all glass blocks. By this method the advantages of the glass blocks are retained with lower cost because of the concrete spacing between the blocks, and much greater strength on account of the reinforced concrete lattice, in which the blocks are set.

Assembly of the various inserts for the wall is made under the most favorable conditions, right in the form, where strict measurements can easily be adhered to and where an accurate layout of the arrangement is possible.

The taper shown in Fig. 6 is for two purposes; that of providing the necessary draft so no difficulty will be encountered in removing the panels 35 with their location and retainers, and that of providing sloping surfaces to shed water and dust.

After the panels have been removed, they are ready for assembly with another set of inserts for another part of the wall, or for another wall. The blocks and frames for another section are assembled between the panels and the completed form delivered to the job.

The frames are preferably releasably secured to the panel by means of dowels or taper pins so that the panels can be removed without disturbing the frames or insert positioning and retaining means.

After the forms are completed it is merely necessary to place the form in its proper position, pour the concrete, and after the concrete has set, remove the panels which release themselves from the frames, then remove the frames from the recesses shown in Figs. 6 and 7, and finally withdraw the tie members or cut off the projecting end. If the tie members are tapered or otherwise removable, the holes left can be grouted in.

I claim:

1. A form for casting concrete walls comprising a face panel for each side of the wall and having each an inside face and an outside face; insert positioning and retaining means on the inside face of one panel for positioning and retaining inserts to be cast within the concrete wall and initially functioning as spacers between said panels; and transverse tying means cooperating between said panels to secure the inserts against displacement during pouring of the concrete.

2. A structure as defined in claim 1; said positioning and retaining means comprising each a rectangular frame removably secured to the inside face of said one panel and located with the major axes in horizontal and vertical alignments and spaced apart to provide a latticework of diagonal channels for pouring of concrete to eliminate air pockets.

3. A structure as defined in claim 1; said positioning and retaining means each consisting of a rectangular frame to encompass the end of an insert, and with said frames located in diagonal series to form a latticework of channels therebetween for pouring of concrete; and in which said transverse tying elements are located within said channels to function simultaneously as supports for reinforcing rods and as means to retain the panels against spreading under fluid pressure of concrete during pouring and previous to setting.

4. A structure as defined in claim 1; said panels having cooperative securing and sealing means for releasably securing the adjacent ends of a series of panels together and provide leakproof joints.

5. A structure as defined in claim 1; said panels each having a groove formed inwardly from each end and extending throughout the height of the panel; and a plate having its respective sides releasably secured in the grooves of the abutting ends of two panels and extending throughout the height of the panels.

6. A structure as defined in claim 1; said panels each having a groove formed inwardly from each edge and extending throughout the circumferential extent of the panel; and coupling members fitting within said grooves; securing means for releasably securing the respective ends of the coupling members in the respective grooves of the abutting ends of the panels to form a continuous leakproof series of forms for a single pouring of concrete.

7. A structure as defined in claim 1; said insert positioning and retaining means comprising a frame including a seat portion in spaced relation to the inside face of the panel for cooperation with the face of an insert, a circumferential ridge to cooperate with the peripheral edges of said face and with the outside of the frame having outwardly divergent walls to provide draft for removal from the concrete after setting thereof and to provide shedding surfaces in the recess formed thereby in the finished concrete wall.

8. A structure as defined in claim 1; said insert positioning and retaining means comprising each a frame having outwardly divergent walls for draft in the form and a water shed in the finished wall, and having a seat portion for cooperation with the face of an insert and spaced from the inside face of the panel to form a recess in the finished wall in front of the insert, and having a circumferential ridge to cooperate with the peripheral edge of the said one face of the insert, and being releasably secured in position by means of dowels to permit retention of the frame in the finished wall while the panels are removed, with the frame thereafter being individually removable from the wall.

9. A structure as defined in claim 1; said insert

positioning and retaining means being located diagonally in series and horizontally and vertically equally spaced to form a latticework of channels for concrete; and closures for the spaces between adjacent corners of the last vertical series in the form for starting the pouring of concrete in the next stage around the projecting halves of inserts from the previous pouring of concrete to form a continuous unbroken pattern.

10. In a form for casting concrete walls; face panels; means for positioning and retaining spacers between said panels, and means for securing the spacers releasably in position between said panels; and in which said means for positioning and retaining consists of rectangular frames removably secured to one of said panels and located with the corners in respective vertical and horizontal series and equally spaced to form a latticework with intervening diagonal channels between the frames and spacers for pouring of concrete; said means for releasably securing said spacers comprising tying elements for securing the panels against spreading under the fluid pressure of the concrete and passing through intersections of diagonal channels to coincidentally function as supports for reinforcing rods.

11. Means for locating and retaining glass blocks in position in a concrete pouring form during the pouring of the concrete comprising a panel for each side of the form; a frame having outwardly divergent peripheral surfaces and terminating inwardly in a ridge portion with an intervening seat to provide a thrust surface for one face of a glass block, and tying elements to tie the panels against spreading under fluid pressure of the concrete during pouring and to secure the glass blocks against displacement.

12. A structure as defined in claim 1; said positioning and retaining means comprising frames removably attached to said inside face of said one panel for encompassing and positioning ends of the inserts, and with the inside face of the other panel being plane with the other ends of the inserts.
